UNITED STATES PATENT OFFICE.

ORLA A. HAYNER, OF MASON, MICHIGAN.

DESIGN FOR A CLOCK CASE.

Application filed July 27, 1928. Serial No. 27,606. Term of patent 7 years.

To all whom it may concern:

Be it known that I, ORLA A. HAYNER, a citizen of the United States, residing at Mason, county of Ingham, State of Michigan, have invented a new, original, and ornamental Design for a Clock Case, of which the following is a specification forming a part thereof, reference being had to the accompanying drawing in which—

I claim:

The ornamental design for a clock case, as shown.

ORLA A. HAYNER.
